UNITED STATES PATENT OFFICE

CLIFFORD NORTON, OF SOUTH ORANGE, NEW JERSEY, ASSIGNOR, BY MESNE ASSIGNMENTS, TO OTIS ELEVATOR COMPANY, A CORPORATION OF NEW JERSEY

DOOR MECHANISM

Application filed January 10, 1929. Serial No. 331,454.

This invention relates to improvements in door operating mechanism and is particularly designed for use with elevator doors.

It is a primary object of the invention to provide a door moving mechanism which will operate with uniformity to open and close elevator doors and which will permit the door to be opened to a limited extent independently of such door moving mechanism.

The above and other objects will appear more fully from the following description when considered in connection with the drawing in which:

15 Fig. 1 is an elevational view of one form which the invention may assume.

Fig. 2 is an enlarged plan view of the apparatus shown in Fig. 1.

Fig. 3 is an elevational view thereof.

20 Fig. 4 is an elevational view of one part of the apparatus, parts being in section, illustrating the limited opening movement of the door.

Fig. 5 is a view similar to Fig. 4 showing 25 condition of the levers when the door is opened in the normal manner.

Fig. 6 is an enlarged detail view of a portion of the construction shown in Fig. 4.

Fig. 7 is a horizontal sectional view on an 30 enlarged scale of a portion of the mechanism shown in Fig. 2.

In the control of elevator doors it is necessary that the door moving mechanism be formed of parts allowing no looseness between the same in the normal movement of the door to open or closed position. At the same time it is desirable to permit a limited movement of the door from closed or near closed position so as to permit passengers 35 to extricate objects caught in the door such for example as portions of their clothing, umbrellas or the like. The construction described below accomplishes the purpose of maintaining the door moving mechanism unyielding in the normal operation thereof but also affords a certain independent opening movement of the door from substantially closed position.

Referring to the details of the drawing 40 45 50 the elevator doors 8 and 9 are shown as of

the two speed type, the door 8 being movable one door width and the door 9 being movable two door widths behind the third or stationary door (not shown).

The doors are designed to be moved by the door moving toggle levers 10 comprising the three links 11, 12, and 13 which are attached respectively to the two movable door sections 9 and 8 and to the elevator shaft wall or other stationary member.

The toggle links 10 may be operated by the manual member 14 or by means of the power devices indicated generally at 15, said power devices being connected by the link 16 to the projection 17 on the toggle link 13.

Other power devices may obviously be substituted for those shown. It will be understood that downward pressure upon the handle 12 or upward pressure through the power device 14 will break the toggle levers and move them to the dotted line position shown in Fig. 1 for opening both doors. The doors may be closed by manual pressure applied directly to the doors or through the toggle levers although preferably spring pressure is applied as by providing a usual door closing spring within the cylinder 15.

Such doors and door moving devices are previously known in this art.

With door moving devices as heretofore constructed the doors have been positively held in completely closed position capable of being opened only by operation of the door moving mechanism. According to the present invention one door section 9 may be moved slightly independently of the operation of the door moving levers.

Independent movement of one of the door sections is accomplished according to the construction disclosed herein by forming the link 11 of two sections 11a and 11b. The section 11a carries a collar 18 rigidly connected to the same and encircling the section 11b so as to be slidable with relation thereto. A similar collar 20 is connected to the outer end of the section 11b and encircles the section 11a in slidable relation to the latter. The collars 18 and 20 are normally drawn toward one another into contacting relation by means of the spring 22 connected

to a suitable projection formed on each collar.

The collar 18 and link section 11a carry a rigid projecting plunger 24 slidably mounted in the bushing 30 carried by the link element 11b and projecting in alignment with the link 11 toward the pivot point 26 connecting the links 11 and 12.

The pivot 26 is formed with a circular bushing 28 mounted for pivotal movement in the bushing 30. The outer ends of the bushing are squared or are formed of other out-of-round construction is indicated in dotted lines in Fig. 6, the squared projecting ends of the member 28 being received in and securely supported by the separated bars constituting the toggle lever 12. The bearing 28 is formed with a diametric opening or recess 32 of a size just sufficient to loosely receive the projecting end of the plunger 24. The transverse opening 32 is arranged to be directed toward the plunger 24 when the toggles are in straight-line position as shown in Fig. 1.

The above described construction causes the bearing 28 to be moved with the link 12 and the plunger 24 to be moved with the link 11 so that a very slight relative turning movement of the links 11 and 12 prevents the entrance of the plunger 24 into the opening 32. If desired the slotted bushing 28 may be mounted on a friction clutch, preferably of the snap action self centering type to permit rotation thereof under certain conditions as, for example, when the door is opened after the plunger 24 has passed through the said bushing.

The operation of the apparatus is as follows:

In normal operation when power is applied through the devices 15, or where the levers are hand-actuated through the manual member 14, the straight-line arrangement of the toggle levers is broken and the doors are moved toward open position. During such movement the tension upon the inner link section 11b in conjunction with the spring 22 maintains the collars 18 and 20 in engagement whereby the link 11 operates as one piece in the usual manner. After a slight relative turning movement of the links 11 and 12 the plunger 24 is prevented from passing into the aperture 32 under any condition so that the link portions 11a and 11b necessarily operate as one member until the door is again closed.

After the door has reached substantially closed position if for any reason it is desired to move the door 9 to slightly open position, for example to the extent of about four inches, such limited movement is permissible with the constructions shown so long as the links 11, 12 and 13 remain in door closed position. The movement of the door 9 independently of toggle lever move-

ment merely causes the plunger 24 to pass into the recess in the bearing member 28. The opening movement of the door under these conditions is limited by the engagement of the collar 18 against a suitable stop lug or against the bushing 30 to allow the desired opening of the door. The spring 22 draws the door 9 to closed position when the latter is released.

While the drawing discloses only the two-speed type of doors with three toggle links it will be understood that the invention is equally applicable to a single movable door requiring only two toggle levers or in fact to any door mechanism employing a pivoted lever.

By means of the construction described above it will be seen that under normal operation the doors may be uniformly moved by the toggle links to either open or closed position by either hand or power means. Whenever desired the door 9 may be moved to a limited extent away from completely closed position without disturbing the door moving mechanism.

Having now described my invention, I claim:

1. In combination with a movable elevator door, means for moving said door comprising a pivoted link having normally a definite length, means permitting variation of said length when said link and door are in one position and means automatically preventing such variation on movement of said link and door to different positions.

2. In combination with a movable elevator door, means for moving said door comprising a pivoted link having normally a definite length, means permitting variation of said length when said link and door are in the positions assumed thereby in door closed position and means automatically preventing such variation on movement of said link and door to different positions.

3. In a door controlling mechanism, toggle links pivotally connected to said door and operative to move said door upon the breaking of said toggle links, one of said links including a yielding connection permitting movement of said door relatively to the other of said links without the breaking of said toggle links and means for locking said connection against yielding, said locking means operating automatically upon the breaking of said toggle links.

4. In a door controlling mechanism, door moving members including a link formed with opposite pivot points, means on said link permitting said pivot points to approach one another, and means controlled simultaneously with door and link movement for automatically resisting the approach of said pivot points toward one another.

5. In an elevator door controlling mecha-

nism, toggle links, an apertured stud movable with one of said links, a projecting element movable with another of said links and aligned with said aperture only when
5 said links are in door closed position, means for accommodating limited independent movement of said door relatively to a portion of said last named link and simultaneously causing said projecting element to pass
10 into the aperture in said stud.

6. In a door controlling mechanism, toggle links operatively connected to said door, means for permitting limited movement of said door independently of movement of
15 said links, said means being operative in one direction only and automatically controlled means for positively preventing such independent movement of said door.

Signed at New York in the county of New
20 York and State of New York this 9th day of
January A. D. 1929.

CLIFFORD NORTON.
